HARRY E. HOLCOMB, OF STRATFORD, CONNECTICUT, ASSIGNOR TO FIBERFRAKS, INC.,
OF NEW YORK, N. Y., A CORPORATION OF NEW YORK

DRIER FOR PAPER-MAKING MACHINES

Application filed June 29, 1928. Serial No. 289,248.

This invention is concerned with the provision of a drier for paper making machines, adapted to receive the wet fiber web from the pulp tank and deliver it in a dry condition.

An object of the invention is to provide a drier in which a break occurring in the fiber web in the course of its passage through the drier does not necessitate stoppage of the machine and the resultant overdrying of a portion of the web.

Another object is to provide a drier which may be substantially enclosed, and in consequence a drier which may be heat insulated as opposed to the present open type driers from which much heat is continually dissipated.

Another object is to provide a drier which is highly efficient in operation due not only to its heat insulating qualities, but due to the manner in which the paper web is subjected to the action of drying air currents.

Another object is to provide a drier in which the use of steam heated rolls is avoided, and the difficulties and disadvantages incidental to the use of such rolls consequently eliminated. Notable among such disadvantages are the matting and ironing of the paper, the sticking of the paper on the rolls when the travel of the web is temporarily stopped, and the consequent breaks in the web caused by such sticking.

Another object is to provide a drier utilizing drying air currents of considerable force and velocity, while at the same time so supporting the paper web that it is sustained against sagging by its own weight and against deflection under the force of such air currents.

Still another object of the invention is to provide a drier which will turn out a uniform, porous, unbroken web of paper and which is therefore peculiarly adapted for use as an element of a continuous process machine.

Other and more general objects of the invention are to provide a drier of simple practical construction which will be rugged, durable and efficient in use and which is well suited to the requirements of economical manufacture and inexpensive operation.

In a preferred embodiment of the inven-

tion, the wet fiber web is stripped from its collector screen by a suction apparatus and passed into the drier where it is received between a pair of endless reticulated supporting webs which carry it in a tortuous path 55 around a suitable series of guiding rollers.

In the course of its travel the web is substantially continually subjected to a strong draft of hot drying air, the foraminous nature of the supporting webs permitting free 60 passage of the air currents over both surfaces of the paper.

Preferably the various runs of paper cooperate with suitable baffle means to direct the course of the drying air currents, and the 65 path of travel of the air current in intimate relationship with the paper is a relatively short one. By virtue of this arrangement I materially improve the action of air drying machines in which the air currents are caused 70 to travel in a long tortuous path over the web and become so thoroughly humidified by the wet paper web that they have lost most of their effectiveness long before they pass to exhaust from the drier.

With the above noted and other objects in view, the invention consists in certain novel features of construction and combinations and arrangements of parts as will be more fully hereinafter described and pointed out 75 in the claims.

The invention may be understood more fully from the following description in connection with the accompanying drawing which is a somewhat schematic, vertical sectional view through a drier embodying the invention, illustrating diagrammatically the pulp tank from which the wet paper web is passed to the drier and the roller for passing the dry paper from the drier to the saturating tank or other apparatus.

A drier chamber or dry house 10 is substantially wholly enclosed, save for the two small openings 11 in one end to accommodate the two horizontal runs of the endless 85 delivery web 12 and the slot 13 in the opposite end through which the dried paper web 14 emerges and is passed over a roller 15.

The delivery web 12, of felt or other suitable material travels around rollers 16 and 100

17 mounted exteriorly and interiorly respectively of the drier. The lower run of the endless web 12 passes closely adjacent a suction head 18 which serves to strip the wet fibrous sheet from the endless collector web 19 upon which the fiber has been deposited in the pulp tank. The suction head also serves to remove some water from the web.

10 The fiber sheet is held against the under face of the lower run of the web 12 by suction and while so held is passed through the opening 11 into the drier chamber where it enters between a pair of endless reticulated supporting webs 20 and 21 preferably of wire mesh or other reticulated material.

15 From the point where the fiber sheet enters between the webs 20, 21 to the point where it leaves the web, the fiber sheet and the supporting webs travel as a unit in a tortuous or serpentine path, first under pairs of lower guiding rollers 22 and then over pairs of upper guiding rollers 23. Each substantially vertical run of the webs from the upper rollers to the lower rollers or vice versa swings 20 back toward the end of the drier which the web has entered. The only longitudinal movement of the web through the drier is accomplished as the web passes from one lower roller to another or from one upper roller 25 to another. By this expedient the web is caused to travel a long distance and is subjected to the action of a considerable quantity of drying air, while it is passing through a comparatively short drying chamber.

30 Baffles extending transversely of the drying chamber cooperate with the webs to direct the course of the air currents. Two sets of such baffles are used, the lower set being of J-shape and the upper set being of inverted J-shape. 35 The hook shaped bottom 24 of each lower deflector rather closely follows the path of the webs around a pair of lower rollers 22 and the vertical leg 25 of this baffle extends upwardly between adjacent vertical runs of the web and terminates between and adjacent a pair of upper rollers 23. The upper baffles on the other hand include hook shaped portions 26 substantially embracing the pairs of spaced upper rollers 23, and depending 40 leg portions 27 which extend downwardly between adjacent runs of the web and terminate midway between and closely adjacent a pair of lower rollers 22.

45 Between the several hooked portions 24 of the lower baffle set are openings through which air currents from a blower delivery pipe 28 disposed near one lower corner of the drier are adapted to enter, a suitable baffle 29 directing the air from the blower upwardly between members 24.

50 Near one upper corner of the drier a second blower delivery pipe is provided which with the aid of suitable baffles 31 directs currents of air downwardly through the inter-spaces formed by the hooked portions 26 of

the upper baffle set. The upwardly flowing air currents from the lower blower pass between the leg of one lower baffle and one upwardly travelling run of the paper web, thence around the top of this leg and downwardly into the space defined by the opposite face of the leg and another downwardly travelling run of the web. Near the bottom of this space the air is exhausted through an outlet port 28a.

70 75 The air currents from the upper blower travel a similar but reversed path, passing downwardly on one side of the leg 27 upwardly on the opposite side thereof and outwardly through a port 32.

80 85 The air exhausted from the ports 28a, 32 may, if desired, be partially or completely dried, mixed with a supply of fresh air and recirculated by the blowers which latter may be inside or outside of the housing 10.

90 95 The means for heating the drying air may be located exteriorly of the drier chamber or may comprise conventional heat generating units of any suitable type located within the chamber, for instance, between the floor and roof of the chamber and baffles 29 and 31 respectively.

100 105 The endless wire mesh web 20 as it leaves the paper web is trained around guiding and driving rollers 34, 35, 36 disposed between the various baffles and the drier wall, while that portion of the web 21 not disposed in paper carrying position is trained over rollers 37, 38 between baffles 31 and the drier roof. The upper web 21 leaves the paper web just as the latter reaches the first one of the last pair of rollers 23 and the lower web leaves the paper just as the latter passes from said last one of the last pair of rollers 23 and is drawn outwardly through the slot 13 by the roller 15.

110 115 Obviously many other roller arrangements might be provided for training the portions of the reticulated webs which are not in engagement with the paper. Obviously also the exact arrangement of the rollers about which the paper web and carrier webs travel as a unit is subject to considerable variation within the spirit of the invention and the scope of the claims. This is also true of the particular disposition of the various baffles, blowers and exhaust ports.

120 125 From the foregoing description it will be seen that break is unlikely to occur in the paper web except as the result of a flaw in the stock or some similar cause and that such breaks do not necessitate stoppage of the drier, since the paper is always securely held between the two carrier webs.

130 The paper leaves the drier in a porous thoroughly dry unmatted condition. The air currents blown with considerable force through a relatively short path, dry the paper effectively and are passed to exhaust before they become sufficiently humidified to lose their efficiency.

Inasmuch as the air currents always flow in the direction of travel of the paper web they tend to assist rather than retard its passage through the drier. Even aside from the carrier webs the paper would not be materially flexed or distorted by air pressure since this pressure is substantially balanced at opposite sides of the paper except at points where the paper web is backed by the hook shaped ends of the deflectors or baffles. As the webs 20 and 21 are of wire gauze they will not absorb any of the water and will let the air contact directly with the paper through the apertures so that the paper is rapidly dried while being firmly supported.

Having thus described my invention, what I claim as new and desire to secure by Letters Patent is:

1. In a drier for paper making machines, a substantially closed chamber having an inlet and outlet at opposite ends, rollers for guiding the web in a substantially serpentine path through the chamber, lower and upper vertical sets of baffles projecting respectively into the U and inverted U loops formed by the adjacent runs of the web and cooperating with said runs to define directing channels for the drying air currents, blower outlets discharging air into the chamber above and below the web, said air passing around each baffle in the direction of the travel of the web, and exhaust ports through which the air escapes after it has passed over the surface of substantially a complete paper loop.

2. In a drier for paper making machines, a substantially closed chamber having an inlet and outlet at opposite ends, rollers for guiding the web in a substantially serpentine path through the chamber, lower and upper vertical sets of baffles projecting respectively into the U and inverted U loops formed by the adjacent runs of the web and cooperating with said runs to define directing channels for the drying air currents, blower outlets discharging air into the chamber above and below the web, said air passing around each baffle in the direction of the travel of the web, and exhaust ports through which the air escapes after it has passed over the surface of substantially a complete paper loop, said baffles each including a hooked end substantially embracing the closed end of each loop and its roller means and backing such portions of the loops against distortion under air pressure.

3. In a drier for paper making machines, a substantially closed chamber having an inlet and outlet at opposite ends, rollers for guiding the web in a substantially serpentine path through the chamber, lower and upper vertical sets of baffles projecting respectively into the U and inverted U loops formed by the adjacent runs of the web and cooperating with said runs to define direct-

ing channels for the drying air currents, blower outlets discharging air into the chamber above and below the web, said air passing around each baffle in the direction of the travel of the web, and exhaust ports through which the air escapes after it has passed over the surface of substantially a complete paper loop, said baffles each including a hooked end substantially embracing the closed end of each loop and its roller means and backing such portions of the loops against distortion under air pressure, the closed end of each loop travelling around a pair of spaced rollers and the adjacent runs of the loops between upper and lower roller sets being inclined relatively to each other and to the baffle between them.

4. In a drier for paper making machines, a chamber, sets of upper and lower rollers over which the paper web to be dried is trained in a series of alternating U and inverted U bends, a set of upper vertical baffle plates pendent into the U bends, a similar series of plates projecting upwardly into the inverted U bends, means for blowing air from opposite sides of the web around the respective baffles in paths defined by the baffles and adjacent runs of the web, and means through which the air passes to exhaust after it has passed substantially completely around each baffle.

5. In a drier for paper making machines, a chamber, sets of upper and lower rollers over which the paper web to be dried is trained in a series of alternating U and inverted U bends, a set of upper vertical baffle plates pendent into the U bends, a similar series of plates projecting upwardly into the inverted U bends, means for blowing air from opposite sides of the web around the respective baffles in paths defined by the baffles and adjacent runs of the web, and means through which the air passes to exhaust after it has passed substantially completely around each baffle, the blower inlets being located adjacent the upper and lower corners of the chamber, and additional baffle means for directing the air currents from said blower means into the spaces between the vertical baffles and the runs of the web.

6. In a drier for paper making machines, a chamber, sets of upper and lower rollers over which the paper web to be dried is trained in a series of alternating U and inverted U bends, a set of upper vertical baffle plates pendent into the U bends, a similar series of plates projecting upwardly into the inverted U bends, means for blowing air from opposite sides of the web around the respective baffles in paths defined by the baffles and adjacent runs of the web, and means through which the air passes to exhaust after it has passed substantially completely around each baffle, each vertical baffle including a lateral extension at its outer end closing the space

between the baffle and one adjacent run of the web.

7. A drier for paper making machines including a pair of endless reticulated carrier webs for conveying the paper therebetween, 5 rollers for guiding the webs in a substantially serpentine path forming U loops, the carrier webs serving to support the paper from both sides during its travel along the sides of said loops from one set of rollers to 10 the other, a baffle projecting into each loop and having an air inlet and an air outlet upon opposite sides adjacent to one end, whereby an air passage is formed within the loop 15 along opposite sides of the baffle, and means for delivering air through the passages to said loops in parallel.

8. A drier for paper making machines including a pair of endless reticulated carrier webs for conveying the paper therebetween, 20 rollers for guiding the webs in a substantially serpentine path forming U loops, the carrier webs serving to support the paper from both sides during its travel along the sides of said loops from one set of rollers to 25 the other, a baffle projecting into each loop and having an air inlet and an air outlet upon opposite sides adjacent to one end, whereby an air passage is formed within the loop 30 along opposite sides of the baffle, and an air supply conduit connected to each of said inlets for delivering air through said passages.

9. A drier for paper making machines including a pair of endless reticulated carrier webs for conveying the paper therebetween, 35 rollers for guiding the webs in a substantially serpentine path forming U loops, the carrier webs serving to support the paper from both sides during its travel along the sides of said loops from one set of rollers to the other, a baffle projecting into each loop and having an air inlet and an air outlet upon opposite sides adjacent to one end, said end 40 having a portion closely adjacent to one of said webs to prevent flow of air therebetween, and the other end of the baffle being spaced from said web to permit the passage of air around the end of the baffle.

10. A drier for paper making machines, including sets of spaced rollers, a pair of carrier webs for conveying the paper back and forth in a serpentine path between said sets of rollers and forming U loops, and baffles 50 projecting into said loops, the outer end of each baffle being disposed closely adjacent to the web to substantially prevent air passage between the baffle and web and the opposite end terminating within the loop and 55 spaced from the web, and an air inlet to each loop between the baffle and web adjacent to the first mentioned end of the baffle.

11. A drier for paper making machines including a pair of endless wire gauze carrier 60 webs for conveying the paper therebetween,

rollers for guiding the webs in a substantially serpentine path forming U-loops, the carrier webs serving to support the paper from both sides during its travel along the sides of said loops from one set of rollers to the other, a baffle projecting into each loop and forming therewith a separate air passage in each loop along opposite sides of said baffle, means for delivering a separate air current to each such passage adjacent to one end thereof, and means for exhausting the air at the opposite end of the passage whereby the web is dried from opposite sides by evaporation of the moisture through the wire mesh.

Signed at Bridgeport, in the county of 75 Fairfield and State of Connecticut, this 27th day of June, A. D. 1928.

HARRY E. HOLCOMB.
